2,242,175

PROCESS OF SEPARATING SOAP STOCK

Benjamin Clayton, Houston, Tex., and Benjamin H. Thurman, Bronxville, N. Y., assignors to Refining, Inc., Reno, Nev., a corporation of Nevada

No Drawing. Application October 5, 1937,
Serial No. 167,470

8 Claims. (Cl. 260—425)

This invention relates to a method of centrifugally separating soap stock from glyceride oils which have been treated with an alkaline refining agent to form such soap stock and more particularly to a method in which an anti-sticking agent is employed during the separation step for preventing constituents of the soap stock from sticking to the walls of the centrifugal bowl and building up a layer thereon.

In refining glyceride oils by processes employing a centrifugal separator for continuously separating soap stock from the refined oil, the industry has been confronted with the necessity of shutting down the centrifugal separator intermittently in order to clean the bowl thereof, since a layer of soap stock, almost invariably, progressively builds up in the centrifugal bowl against the outer wall thereof. When this layer reaches a thickness at which clean separation between the soap stock and the oil no longer takes place, the centrifugal must be dismantled and the layer scraped from the bowl. Ordinarily such a cleaning operation must be performed every few hours and seriously reduces the total output of a refining operation employing centrifugals.

Even before it becomes necessary to shut down the centrifugal for cleaning purposes, the increasing layer reduces the capacity of the centrifugal so as to progressively decrease the amount of oil and soap stock that may be passed therethrough. Not only is the cubic content of the bowl reduced, but the neutral zone of separation is progressively moved toward the center of the centrifugal so as to cut down the centrifugal force causing separation. As the layer builds up, soap stock begins to discharge with the refined oil and when the amount of soap stock discharging therewith reaches a quantity which can no longer be tolerated, the machine is stopped and cleaned. Even before this happens, the force tending to push the layer of soap stock out of the machine will at times overcome the adherence of the layer to the bowl causing sudden releasing and slipping of this layer. When this happens, an unbalanced condition is produced and the separated columns of oil and soap stock oscillate in the centrifugal so that soap stock is intermittently discharged with the refined oil and the refined oil is intermittently discharged with the soap stock. Thus there is constant danger of the refined oil being contaminated with soap stock even before the neutral zone is shifted far enough to cause soap

stock to be discharged continuously with the refined oil.

The above discussed layer of soap stock is predominantly made up of the gummy, proteinaceous constituents of the soap stock. Certain of these constituents adhere to the outside wall of the centrifugal bowl, then other particles of the same material cohere to those already adhered to the bowl wall. The resultant layer is a sticky, gummy material which is extremely difficult to clean from the bowl wall and is frequently called "liver" in the art because of its appearance and consistency. Applicant has found that if the initial adherence of this gummy material to the wall of the bowl can be prevented, the layer will no longer build up. This initial adherence is promoted by the refrigerating effect of a rapid rotating centrifugal bowl in contact with the atmosphere. Separation of soap stock from glyceride oil is ordinarily carried on at a temperature considerably above room temperature. Contact between the centrifugal bowl and gases at room temperature cool the walls of the bowl and therefore the material in contact therewith.

10 The initial adherence of the gummy particles to the wall of the bowl may be prevented by applying heat externally to the wall of the bowl or supplying a heating medium internally of the bowl in order to compensate for this loss of heat or even raise the temperature of the material in contact with the bowl walls as is disclosed in the copending application, Ser. No. 34,258, filed August 1, 1935, of Benjamin Clayton, which has matured into Patent No. 2,100,277, issued 15 November 23, 1937.

In accordance with the present invention this initial adherence may also be prevented by incorporating an anti-sticking agent with the materials being separated so that the tendency of the gummy particles to stick to the wall of the bowl is overcome. Certain materials, hereinafter described, appear to render the gummy particles less sticky, or produce a layer of material adjacent the outer wall of the bowl which prevents the sticky materials coming into contact therewith.

It is, therefore, an object of the present invention to provide a process of centrifugally separating soap stock and glyceride oils in which an anti-sticking agent is employed for preventing initial adherence of gummy or sticky materials contained in soap stock to the outer wall of the centrifugal bowl.

It is a further object of the present invention to provide a process of separating soap stock from

glyceride oil employing an anti-sticking agent to eliminate or reduce the heating of the centrifugal bowl for the prevention of the building up of a layer of soap stock therein.

The anti-sticking agents of the present invention may be introduced into the process so that they are present in the materials adjacent the outer wall of the centrifugal during centrifugal separation. Ordinarily the anti-sticking agent is introduced into the process some time prior to centrifugal separation so that it will be thoroughly admixed with all of the materials undergoing separation, but it is within the contemplation of the present invention to introduce such an anti-sticking agent into the centrifugal bowl so that it contacts and mixes with only the separated soap stock adjacent the outer wall of the centrifugal.

One anti-sticking agent which has been successfully employed is karaya gum. This material may be introduced into the process at any time prior to separation or into the centrifugal itself as above described. It is relatively inert with respect to the substances employed in the refining operation and may therefore be mixed either with the refining solution or the oil prior to refining or it may be injected into the mixing zone wherein the refining solution and oil are mixed. Also, it may be injected into the mixture of oil and soap stock being delivered to the centrifugal or, as indicated above, directly into the centrifugal bowl adjacent the outer periphery thereof. This material appears to render gummy particles of the soap stock less adherent to the walls of the bowl and to also provide a thin layer of material on the walls of the bowl to which the said particles will not adhere.

The karaya gum separates with the soap stock so as not to contaminate the neutral oil, and the nature of this material along with the small amounts necessary for performing the anti-sticking function does not impair the value of the soap stock. It is, therefore, unnecessary to separate the karaya gum from the soap stock.

Other anti-sticking agents which may be employed are certain alcohols, for example, those which are sufficiently volatile to be recovered from the soap stock and oil. Aliphatic monohydric alcohols having less than six carbon atoms, for example, ethyl, butyl, iso-propyl, propyl and amyl are satisfactory. Also the esters, for example the acetic esters of such alcohols, as well as certain polyhydric alcohols having the requisite volatility and their esters, can be employed. These materials are preferably admixed with either the oil or the refining solution prior to refining or injected into the mixing zone, since they also have an additional function of reducing the saponification of neutral oil during the neutralization step. However, they perform their anti-sticking function even if mixed with the materials entering the centrifugal or with the soap stock in the bowl after it has been separated from the oil.

Also, the alcoholates, such as sodium or potassium alcoholates, may be employed as the anti-sticking agent since such compounds liberate alcohol and caustic alkali upon contact with water. For this reason the alcoholates are preferably added with the alkaline refining solution or added in the mixing zone for the refining solution and glyceride oil. The alcohol liberated from the alcoholates upon contact with the water of the refining solution also functions as inhibitors for the saponification of material during the neutralization step as is the case when alcohols are added as the anti-sticking agent.

Furthermore, the alcohols, either those originally added or those liberated from the alcoholates, have the additional function of cutting down the entrainment of neutral oil in the soap stock during separation. However, the amount of these materials necessary to prevent sticking is considerably smaller than the amount necessary to substantially inhibit the saponification of neutral oil and the entrainment of neutral oil in the soap stock, although the employment of larger quantities does not interfere with the prevention of adherence of soap stock to the walls of the centrifugal bowl. The major portion of the alcohols discharge from the centrifugal with the soap stock. This portion, as well as the small portion discharging with the refined oil, may be recovered, if desired, for re-use in the process by vaporizing the alcohol and then condensing it.

Other agents which may be employed to prevent sticking are relatively concentrated aqueous solutions of salts which have no deleterious reaction with the soap stock or neutral oil and which have high solubility in water. Alkaline metal salts are in general suitable, such as sodium sulphate, chloride acetate, carbonate and silicate, as well as the equivalent potassium salts. These materials should be, in most cases, added to the process subsequent to the neutralization step, since their presence is undesirable during the neutralization step. They may be mixed with the materials being delivered to the centrifugal or they may be delivered into the centrifugal bowl so as to mix only with the soap stock adjacent the outer periphery thereof. Since these materials have a much greater specific gravity than the soap stock, they provide a layer of material between the soap stock and the outer wall of the centrifugal bowl so that the gummy materials contained in the soap stock are prevented from contact with the outer walls. These materials will also function to make the soap stock heavier and cause it to more easily separate from the refined oil if they are used in sufficient amounts. The amount necessary to prevent sticking and building up of a layer of soap stock in the centrifugal bowl is considerably less than that required for substantially increasing the weight of the soap stock column in the centrifugal, although larger quantities do not interfere with the prevention of sticking.

Mixtures of the various materials above mentioned may also be employed as the anti-sticking agent. As to the amount of the various materials which should be employed, it is impossible to give definite figures. This amount will depend upon the type of oil being refined and the amount of gummy materials present in the oil. Ordinarily a very small amount, less than 1% of the oil being refined, is sufficient although, as hereinbefore indicated, larger quantities may be employed.

The process of the present invention is particularly adapted for employment with continuous processes of refining glyceride oils since a centrifugal separator is ordinarily employed therewith. However, it may be employed whenever soap stock is separated from glyceride oils irrespective of whether the neutralization to produce the soap stock has been effected by a continuous mixing or a batch mixing step and irrespective of whether the oil is heated prior to the neutralization or the mixture is heated subsequently to the neutralization.

By the use of the term "anti-sticking agent," as employed in the claims, we intend to define

and embrace and be restricted to an agent, in addition to the neutralizing reagent which is introduced to the mixture and functions to prevent the adherence of the sticky components of the soap stock to the centrifugal bowl and the building up of a layer known in the art as "liver" which shifts the neutral zone and thus prevents clean separation of the soap stock and the oil, necessitating frequency of shutdowns; and the term is likewise restricted to an agent which will have no deleterious reaction or effect upon the soap stock or the neutral oil and, moreover, of a character which will not interfere with the reaction between the neutralizing agent and the fatty acids and other impurities contained in the crude oil being refined.

While we have described the preferred embodiments of our invention and have given possible theories of operation, it is understood that we are not to be limited to any theories of operation and that the details of the process of the present invention may be varied within the scope of the following claims.

We claim:

1. In the process of continuously separating soap stock from alkali treated glyceride oils, which includes, delivering a mixture of said soap stock and glyceride oil to a rapidly rotating centrifugal bowl in which the soap stock collects adjacent the outer wall of the bowl prior to being discharged therefrom and constituents of the soap stock tend to adhere to said wall of the bowl, and separately discharging said soap stock from said bowl, the improvement which comprises, incorporating an anti-sticking agent with at least said soap stock adjacent the wall of said bowl to prevent said constituents from adhering to said wall.

2. In the process of continuously separating soap stock from alkali treated glyceride oils, which includes, delivering a mixture of said soap stock and glyceride oil to a rapidly rotating centrifugal bowl in which the soap stock collects adjacent the outer wall of the bowl prior to being discharged therefrom and constituents of the soap stock tend to adhere to said wall of the bowl, and separately discharging said soap stock from said bowl, the improvement which comprises, incorporating an anti-sticking agent comprising karaya gum with at least said soap stock adjacent the wall of said bowl to prevent said constituents from adhering to said wall.

3. In the process of continuously separating soap stock from alkali treated glyceride oils which includes delivering a mixture of said soap stock and glyceride oil to a rapidly rotating centrifugal bowl in which the soap stock collects adjacent the outer wall of the bowl prior to being discharged therefrom and constituents of the soap stock tend to adhere to said wall of the bowl, and separately discharging said soap stock from said bowl, the improvement which comprises, incorporating an anti-sticking agent comprising an aliphatic monohydric alcohol having less than six carbon atoms with at least said soap stock adjacent the wall of said bowl to prevent said constituents from adhering to said wall.

4. In the process of continuously separating soap stock from alkali treated glyceride oils which includes delivering a mixture of said soap

stock and glyceride oil to a rapidly rotating centrifugal bowl in which the soap stock collects adjacent the outer wall of the bowl prior to being discharged therefrom and constituents of the soap stock tend to adhere to said wall of the bowl, and separately discharging said soap stock from said bowl, the improvement which comprises, incorporating an anti-sticking agent comprising a relatively concentrated aqueous solution of a water soluble salt of an alkali metal with at least said soap stock adjacent the wall of said bowl to prevent said constituents from adhering to said wall.

5. The process of continuously separating soap stock from a glyceride oil previously treated with an alkaline refining agent, which comprises, delivering a mixture of said soap stock and oil to a rapidly rotating centrifugal bowl, incorporating with said mixture prior to delivering the same into said bowl an anti-sticking agent for preventing the adherence of constituents of said soap stock to the outer wall of the bowl, whereby said soap stock will substantially uniformly discharge from said bowl, and separately discharging said soap stock and said oil from said bowl.

6. The process of continuously separating soap stock from a glyceride oil previously treated with an alkaline refining agent, which comprises, delivering a mixture of said soap stock and oil to a rapidly rotating centrifugal bowl, incorporating with said mixture prior to delivering the same into said bowl an anti-sticking agent comprising karaya gum for preventing the adherence of constituents of said soap stock to the outer wall of the bowl whereby said soap stock will substantially uniformly discharge from said bowl, and separately discharging said soap stock and said oil from said bowl.

7. The process of continuously separating soap stock from a glyceride oil previously treated with an alkaline refining agent, which comprises, delivering a mixture of said soap stock and oil to a rapidly rotating centrifugal bowl, incorporating with said mixture prior to delivering the same into said bowl an anti-sticking agent comprising an aliphatic monohydric alcohol having less than six carbon atoms for preventing the adherence of constituents of said soap stock to the outer wall of the bowl, whereby said soap stock will substantially uniformly discharge from said bowl, and separately discharging said soap stock and said oil from said bowl.

8. The process of continuously separating soap stock from a glyceride oil previously treated with an alkaline refining agent, which comprises, delivering a mixture of said soap stock and oil to a rapidly rotating centrifugal bowl, incorporating with said mixture prior to delivering the same into said bowl an anti-sticking agent comprising a relatively concentrated solution of a water soluble salt of an alkali metal for preventing the adherence of constituents of said soap stock to the outer wall of the bowl, whereby said soap stock will substantially uniformly discharge from said bowl, and separately discharging said soap stock and said oil from said bowl.

BENJAMIN CLAYTON.
BENJAMIN H. THURMAN.
